UNITED STATES PATENT OFFICE.

LOUIS A. HOERR, OF ST. LOUIS, MISSOURI.

CARLINE.

1,322,694.

Specification of Letters Patent. Patented Nov. 25, 1919.

Application filed December 14, 1914. Serial No. 877,058.

To all whom it may concern:

Be it known that I, LOUIS A. HOERR, a citizen of the United States of America, residing at the city of St. Louis, State of Missouri, have invented a certain new and useful Carline, of which the following is such a full, clear, and exact description as will enable anyone skilled in the art to which it appertains to make and use the same, reference being had to the accompanying drawings, forming part of this specification.

My invention relates to a carline, and its object is to provide a carline, preferably formed of angle iron or other similar structural material, which can be placed in position or removed therefrom while the roof of the car is in place, and which, at the same time, will be so locked in position that it cannot become accidentally detached from the side plates of the car.

In the accompanying drawings, which illustrate one form of carline made in accordance with my invention, Figure 1 is a cross section showing so much of a car as is necessary to illustrate my invention; Fig. 2 is a top plan view of one end of the carline; Fig. 3 is an end view showing the manner of securing the ends against accidental displacement; Fig. 4 is a bottom plan view of the knee iron; Fig. 5 is a plan view of the knee iron; and Fig. 6 is a side elevation of the knee iron; and Fig. 6 is a section taken on the line 6-6 of Fig. 1.

Like marks of reference refer to similar parts in the several views of the drawings.

10 represents the side plates of a car, 11 the filler beams, 12 the ridge pole, and 13 the roof sheathing, all of which parts may be of any usual or well-known construction. The carline consists of a tie beam 15 and truss beam 16, both preferably formed of angle iron, a strut 17, and two knee irons 18 secured to the ends of the beams 15 and 16 by means of bolts or rivets 19. The filler beams 11 are supported by the truss beams 16 and are secured thereto by means of bolts or rivets 20. Each of the knee irons 18 consists of a plate 21 adapted to bear against the side plate 10, a plate 22 extending at right angles to the plate 21 and a web 23 perpendicular to the plates 21 and 22. The bolts or rivets 19 for fastening the tie beam 15 and truss beam 16 to the knee irons extend

through the holes 24 formed in this web 23. The plate 21 is provided below the plate 22 with a projecting portion 25 forming a seat for a U-bolt 26 adapted to pass through openings in the plate 21 and through the side plate 10 of the car. The projecting portion 25 is provided with a lug 27 which is adapted to be bent up around the U-bolt 26 after it is in position, as best shown in Fig. 1, thus preventing the accidental displacement of the bolt. The ends of the U-bolt 26 are provided outside of the side plates 10 with nuts 28 which are prevented from being accidentally detached from the bolt by means of a plate 29, the ends 30 of which may be bent up, as shown in Fig. 2 and the left hand side of Fig. 3, so as to form a nut lock.

It will be evident that my carline may be either placed in position or removed therefrom without in any way disturbing the roof 13 of the car, which is not true of such carlines as are provided with knee irons which extend over the side plate of the car. At the same time, by means of locking the U-bolt 26, both by means of the lugs 27 and the nut lock 29, the accidental displacement of the carline is absolutely prevented, so that the structure is as dependable as one in which the knee irons project over the tops of the side plates. In the construction shown in the drawings, the plate 21 is shown as projecting between the ends of the truss and tie beams and the side plates 10 of the car. This, however, is not essential to the construction. Many other changes may also be made in the form of construction of my carline without departing from my invention.

Having fully described my invention, what I claim as new and desire to secure by Letters-Patent of the United States is:

1. A knee iron for carlines adapted to bear against the side of a car, said knee iron having a seat for receiving a fastening device, a web to engage with the carline beams, and locking means for the fastening device situated adjacent to said seat.
2. A knee iron for carlines adapted to bear against the side of a car, said knee iron having a seat for receiving a fastening device, a web to engage with the carline beams, and bendable locking means formed integral with the said knee iron and situated adjacent to said seat.
3. A knee iron for carlines adapted to

bear against the face of the side plate of a car, said knee iron having a web adapted to be secured to the beams of a carline, a seat to receive the curved portion of a **U**-bolt, and a malleable lug adapted to be bent into position to lock the **U**-bolt against removal.

4. A knee iron for carlines adapted to bear against the face of the side plate of a car, said knee iron having a vertical web adapted to be secured to the beams of a carline, a horizontal plate arranged below said web on which the beams are adapted

to bear, a seat for the curved portion of a **U**-bolt arranged below said plate, and a malleable lug arranged below said seat and adapted to be bent into position to lock the **U**-bolt against removal.

In testimony whereof, I have hereunto set my hand and affixed my seal in the 20 presence of the two subscribing witnesses.

LOUIS A. HOERR. [L.s.]

Witnesses:

W. A. ALEXANDER,
G. M. SHORE.
